UNITED STATES PATENT OFFICE

JOHN F. JOHNSON, OF BELLEVUE, PENNSYLVANIA, ASSIGNOR TO PITTSBURGH PLATE GLASS COMPANY, A CORPORATION OF PENNSYLVANIA

CLAMP FOR PLATE GLASS RACKS

Application filed April 26, 1930. Serial No. 447,752.

The invention relates to a clamp or holder for a plate glass rack designed to secure the glass against movement on the rack when the rack is being moved from one position to another. The invention has for its principal objects, the provision of an improved clamp of simple construction, which can be easily applied and released, which holds the glass securely at all times, and which will hold a stack of glass regardless of the number of sheets in the stack. One embodiment of the invention is shown in the accompanying drawings, wherein:

Figure 1 is an end elevation of a plate glass rack equipped with the improved clamps. Fig. 2 is a section on the line II—II of Fig. 1. Fig. 3 is a side elevation of the rack. Fig. 4 is an enlarged detail view showing the pawl and ratchet adjustment of the clamping arm. And Fig. 5 is a detail showing in side elevation the means for holding the pawl in unlocking position.

The rack itself is of ordinary construction comprising a base 1 on which are mounted the inclined uprights 2, 2 carrying the transverse strips 3, 3. The rack is provided just above the base with a pair of shoulders 4, 4, upon which the edges of the glass sheets 5 are supported. The stack of sheets 5 rest against the inclined side faces of the rack, as indicated in Fig. 1 and are in no danger of being displaced as long as the rack remains stationary. When it is moved from place to place, however, by means of an overhead crane, it becomes necessary to provide means for holding each stack of sheets in position and the applicant's clamp or holder is designed to meet this requirement. Two clamps are shown, one for each set of sheets, but it will be understood that the two constructions are the same so that a description of one will be sufficient. The support for the clamp comprises the brackets 6, 6 secured to the end members 2, 2 by means of the bolts 7, such brackets serving as a support for the horizontal shaft 8 which carries the two clamps. Mounted for rotation on the end of the shaft 8 is the block 9 and swivelled in this block is the end portion 10 of the clamping arm, such clamping arm

comprising a portion 11 which extends laterally from the portion 10, and a portion 12 which extends at right angles to the portion 11. Mounted loosely for rocking movement upon the end of the portion 12 is a plate 13, such plate carrying on its front face a felt sheet 14 for engaging the face of the outer sheet of glass.

In order to hold the end 10 in its various positions of adjustment, a pawl and ratchet 60 is provided, as indicated in detail in Figs. 4 and 5. The ratchet 15 is secured to the end 10 and is engaged by a pawl 16 pivoted at 17 and held normally in engagement with the teeth of the ratchet by means of the spring 65 18. The pawl is provided with a handle 19 by means of which it may be swung to release position. It is held in release position by means of the detent 20 yieldingly pressed upward by means of the spring 21 and 70 adapted to engage a recess 22 in the lower side of the handle 19 when the handle is swung to release position. The detent also serves to prevent the pawl from moving from operative position, as will be seen by 75 reference to Fig. 5. This pawl and ratchet adjustment permits the clamp to be adjusted to hold stacks of glass sheets of different thickness up to the capacity of the rack.

The clamp is shown in operative position 80 in full lines in the drawings and at such time the glass sheets are securely held in position against the inclined face of the rack. When it is desired to release the clamp, the arm 12 is swung upward around the horizontal 85 shaft 8, the arc of swing being shown in Fig. 3. The device when thus moved from operative position reaches the dotted line position marked A in Figs. 1 and 2, at which time it lies at the end of the rack and out 90 of the way, so that it does not interfere with the removal of the glass from the rack or the placing of the glass upon the rack. When in operative position, there is no tendency of the device to become disengaged, since 95 the force of gravity tends to move the plate 13 downward, but such downward movement can not occur because of the inclination of the sheets 5 so that the clamp tends to tighten rather than to release. The device is thus 100

safe and positive in its holding action, but at the same time can be quickly and easily released and when in release position is entirely out of the way.

5 What I claim is:

1. The combination with a rack for carrying plate glass sheets having one side inclined to the vertical, of a clamp or holder for glass sheets carried by the rack and resting against said side, comprising a bracket secured to one end of the rack, a block pivoted on the bracket for movement about a horizontal axis, an arm mounted on the block for adjustment about a vertical axis, said arm comprising a part extending substantially at right angles to said vertical axis and a second part extending at substantially right angles to the first part, a plate for engaging the glass mounted for rocking movement on the end of said second part, and means for releasably holding the arm in its various positions of adjustment about said vertical axis.

2. The combination with a rack for carrying plate glass sheets having one side inclined to the vertical, of a clamp or holder for glass sheets carried by the rack and resting against said side, comprising a bracket secured to one end of the rack, a block pivoted on the bracket for movement about a horizontal axis, an arm mounted on the block for adjustment about a vertical axis, said arm comprising a part extending substantially at right angles to said vertical axis and a second part extending at substantially right angles to the first part, a plate for engaging the glass mounted for rocking movement on the end of said second part, and means for releasably holding the arm in its various positions of adjustment about said vertical axis, said means comprising a pawl and ratchet.

In testimony whereof, I have hereunto subscribed my name this 21st day of March, 45 1930.

JNO. F. JOHNSON.
